UNITED STATES PATENT OFFICE

2,605,707

POWER-DRIVEN FLUID PUMP

Ronald Frederick Worlidge, London, England

Application May 4, 1946, Serial No. 667,405
In Great Britain August 4, 1944Section 1, Public Law 690, August 8, 1946
Patent expires August 4, 1964

1 Claim. (Cl. 103—5)

1

The present invention relates to power driven fluid pumps and is especially but not exclusively concerned with hydraulic fluid pumps suitable for operating aircraft or similar hydraulic systems.

The pump is of the kind operated in two stages by two pumping units driven by a common shaft, said units acting in succession on the working fluid, and the second stage pumping unit being a piston pump having one or more radial cylinders whose pistons are operated on their working stroke by a cam or eccentric with which they are held in contact by the pressure of the fluid supplied to them by the first stage unit, which may be of the gear pump type.

In accordance with the invention the output of the pump is controlled by controlling the output pressure of the first stage (thereby varying the effective stroke of the second stage pistons) zero output being obtained by reducing the output pressure of the first stage to below the minimum required to restore the second stage pistons. This minimum pressure will normally be determined by the pressure required to open the spring loaded inlet valves of the second stage cylinders.

The output of the pump may be automatically and progressively controlled in accordance with variations in the output pressure by applying that pressure to a valve which when a predetermined delivery pressure is reached opens and relieves the interstage pressure.

Alternatively the first stage pressure may be relieved back to its delivery side by a valve which is mechanically operated. The mechanical operating means may be actuated manually or in accordance with the movement of a member operated by the output of the pump. For example, if the pump is used to supply actuating fluid to a hydraulic ram, mechanical coupling means may be provided whereby upon the ram reaching the limit of its travel the relief valve will be opened, thus off loading the second stage and reducing the output of the pump to zero.

According to a further important feature of the invention the first stage of the pump has a capacity considerably exceeding that of the second stage, so that under high altitude flying conditions notwithstanding the reduction in efficiency of the first stage by a high vacuum on its inlet side, it will still be able to supply the second stage to its full capacity, so that the efficient working of the pump will not be impaired.

In the preferred construction the first stage delivers to the second stage through non-return valves, whilst the second stage discharges

through non-return valves to the pump delivery outlet, whereby any desired delivery and pressure may be obtained in accordance with the speed of rotation of the shaft. Preferably also the first stage pumping unit is of the gear pump type.

In the construction example of pump according to the invention hereinlater described and illustrated the fluid to be pumped is fed to, or drawn by the first stage of the pump which consists of two gears in mesh, one driver and one driven, the said gears being enclosed in a casing so formed that when the gears are rotated fluid is passed round in the teeth from one side to the other; the fluid is then fed by this first stage to the second stage which consists of one or a number of pistons, so arranged that each piston can be forced in one direction only by rotating a cam or eccentric crank.

The motive power required to move the pistons in the opposite direction to that imposed by the cam or eccentric is supplied entirely by the fluid, delivered under pressure by the first stage of the pump, acting on the said pistons, and by so arranging non-return valves between the pistons and the first stage delivery, and also between the pistons and the outlet from the pump, the second stage can be caused by simultaneously rotating the driving gear of the first stage and cam or eccentric of the second stage to deliver fluid at any desired pressure.

The pump also includes a valve which is so arranged that when the output pressure of the second stage reaches a predetermined maximum, it acts upon the said valve in such a manner as to cause it to move against a spring or other resisting force and so pass fluid from the delivery of the first stage, either to drain, or to the inlet of the first stage thus reducing, either wholly or in part, the pressure at which fluid is being delivered by the first stage, and by so doing removing either completely, or in part, the motive power necessary to move the pistons of the second stage in the direction opposite to that imposed by the rotating cam or eccentric. The pistons will therefore be moved to one end of their travel by the rotating eccentric, but will fail, either completely or in part, to make the return stroke necessary to maintain continuous pumping; thus the output of the second stage will be reduced, due to the reduction in the stroke of the pistons, to a quantity which may be zero or between zero and the maximum capacity which is determined by the size and full normal stroke of the 55 piston or pistons.

In order that the invention may be clearly understood and readily carried into practice it is illustrated by way of example only, by the accompanying drawings, in which:

Figure 1 is a central longitudinal section of the preferred construction of pump according to the invention;

Figure 2 is an end elevation, with the right hand cover plate removed, in the plane X—X of Figure 1 with the cylinder block removed, and looking in the direction of the arrow II;

Figure 3 is an end elevation with the left hand cover plate removed, in the plane Q, Q of Figure 1, looking in the direction of the arrows;

Figure 4 is in part a cross-sectional view in the plane A—A of Figure 1 and in part an elevation with the right hand cover plate removed, in the plane X—X of Figure 1 looking in the direction Y—Y.

Figure 5 is a longitudinal section on the line B—C of Figure 2, with the cylinder block not sectioned and

Figure 6 is a plan view of the pump.

Referring to the drawings the pump comprises an outer casing formed by a cylindrical body 1 closed at its ends by right and left hand cover plates 2 and 3 respectively, which carry the roller bearings 4 for the inner end of the pump shaft 5 and 6 for the outer portion of shaft 5. On the outer side of bearing 6 the shaft 5 is encircled by a sealing device 7 to prevent any escape of liquid from the interior of the pump.

Within the cylindrical body 1 is a partition 8 which carries an intermediate roller bearing 9 for the shaft 5 and divides the interior of the pump body into two chambers. The left hand chamber contains the gear pump unit and the right hand chamber contains the piston and cylinder pump unit. The body 1 and the cover plates 2 and 3 are held in assembly by a number of peripherally spaced bolts 10.

The gear pump unit comprises a pair of intermeshing gears 11 and 12, of which the gear 11 is mounted on shaft 5 and the gear 12 is mounted eccentrically on a spindle 13 supported at its ends by cover plate 3 and partition 8. The two gears 11 and 12 rotate in circular recesses cut in the pump body 1 and the oil or other working fluid admitted at inlet opening 14 is conducted to the gear pump and admitted to a space 15 on one side of the gears 11 and 12. After passing through the gears and developing a pressure dependent upon their rotation, the oil passes into a space which communicates through a port 16 with an annulus 18 on the opposite side of partition 8, leading on the one hand to the valve 17 and on the other hand to the inlet valves 24 of the piston pump unit.

The valve 17 is disposed between cover plate 3 and partition 8, and the annulus 18 communicates through port 35 with the chamber below the valve 17 (see Fig. 5). The part of the valve chamber above the valve 17 communicates through passage 37 in cover plate 3 with the part annular passage 36 leading to the space 15 on the suction or inlet side of the gear pump unit or alternatively to a drain connection 40. The operation and function of valve 17 will be herein-after explained in detail.

On the right hand side of partition 8 in Figure 1 the cylinder block 19 fits into the casing 1. This block is bored radially to receive a plurality of cylinders 20 in which slide pistons 21. These pistons make peripheral contact with an eccentric

cam ring 22 mounted on the shaft 5 through the intermediary of a needle roller bearing 23.

The supply of oil to the cylinders 20 and its discharge therefrom is controlled by double valves fitted into bores in the cylinder block 19 between the cylinders. The said valves comprise an inlet valve portion 24 and an outlet valve portion 25 which are controlled by springs 26 between the two valves and a spring 27 acting on the outlet valve 25. The inlet valve 24 controls a port communicating with annular passage 18 and the outlet valve 25 controls a port leading into discharge annulus 28 which leads to delivery outlet 29 (Fig. 6). In the bore in which the double valve 24, 25 moves is a port which communicates through passage 30 with the interior of an adjacent cylinder 20. As the pistons 21 reciprocate in cylinders 20 the oil enters the cylinders through valves 24 and passages 30 and leaves the cylinder through the same passages 30 and outlet valves 25. Rubber or other packing rings 31 and 32 are provided between the cylinder block 19 and the cover plate 2 to reduce internal leakage.

On their outward or working strokes the pistons 21 are positively driven by the eccentric 22, and instead of being restored to their radially inward position by non-working strokes produced by springs or the like, the pistons 21 are forced 30 inwardly simply by the pressure of the oil entering the cylinders 20 from the gear pump or first stage unit of the pump.

Thus the pressure attained in the first stage of the pump is used to load the pistons against the driving power of the eccentric 22. This arrangement renders it possible to reduce the output of the pump to zero by reducing wholly or in part the pressure which loads the pistons 21 against the driving eccentric 22, thus reducing 40 the effective stroke of the pistons by restricting the return stroke which the pistons are able to make before the eccentric 22 again forces them outwards on the next working stroke. The delivery will be reduced to zero but maximum pressure is attained when the first stage pressure applied to the pistons 21 approaches zero, so that the pistons 21 perform no inward strokes at all and therefore also no outward or delivery strokes.

The above action results from the use of the interstage valve 17 already referred to. This is a poppet type of valve the underside of which is subject to the piston loading pressure produced by the first stage of the pump, which reaches it through passage 16, annulus 18 and port 35. This pressure acts on the annular surface surrounding the valve stem, whilst the delivery pressure of the pump produced by its second stage, acts on the end of the valve stem. This delivery pressure reaches the end of the valve stem through a passage 31 (Figures 2 and 4 and indicated in dotted lines in Figure 5) passing through the cylinder block 19 from the delivery annulus 28, and the radial passage 32 (Figure 2). The movement of the valve under the action of these pressures is controlled by the double spring arrangement comprising the weak spring 33 and the strong spring 34 acting on the head of the valve in a direction contrary to the oil pressure. These springs are sufficiently strong to maintain a certain maximum first stage pressure, but the addition of the delivery pressure to the valve stem reduces the required pressure from the first stage and with an increasing delivery pressure a decreasing first stage pressure will result.

With this arrangement it is possible by correctly proportioning the valve 17, to control the pressure of the first stage in relation to the delivery pressure and thus control the loading pressure of the second stage pistons by means of the delivery pressure, which, when it reaches a predetermined value, is able to hold the valve 17 wide open with no assistance from the first stage pressure; thus the first stage pressure is permitted to flow back to the suction side of the first stage at a pressure which is insufficient to open the inlet valves 24 of the second stage. Any surplus oil delivered by the second stage pistons during the final part of their operation escapes to suction through ports 46 when valve 17 is fully opened by the delivery pressure acting on the end of the stem. It will be seen that the position of these ports 46 controls the maximum possible opening of the valve 17. Consequently, the cylinders 20 do not fill and no movement of the pistons 21 radially inwards for subsequent outward movement by the eccentric ring takes place. At intermediate delivery pressures the loading of the springs 33 and 34 will be required to be borne to a greater extent by the first stage pressure and the resultant pressure in the annulus 18 may then be sufficient partially to open the inlet valves 24, and drive the pistons 21 inwardly to a reduced extent, so that the working stroke of the pistons is reduced and the delivery correspondingly reduced.

Preferably the first stage of the pump is given at least twice the capacity of the second stage, so that when flying at high altitudes the efficiency of the first stage may be reduced, by reduction of its inlet pressure, by 50% without starving the second stage, thus improving the efficient working of the pump as a whole. The 50% of remaining capacity will be sufficient to both operate and supply the second stage to full capacity. By this means high altitude conditions up to some 40,000 feet can be accommodated without the necessity for pressurising the pump inlet by a separate device and without unduly increasing the prior consumption of the pump, since the maximum first stage pressure is only some 10 to 12% of the final delivery pressure. Therefore an increase in capacity will only reduce the overall efficiency by a relatively small percentage.

It will be understood, of course, that the delivery pressure will be dependent upon the load on the pump i. e. will be high when the load is high, and low at small loads. When the load is zero, the delivery pressure will be zero, and the first stage output will be maximum, whereas when the load is maximum the delivery pressure will be maximum and the first stage pressure will be minimum, thereby reducing the delivery to zero. Under this last condition of running the power taken by the pump will be almost zero since the delivery will be zero although the pressure is maintained.

Having completed the aforementioned sequence of operations the quantity of fluid delivered by the second stage will not increase unless or until the delivery pressure of the second stage is so reduced that the aforementioned

springs 33 and 34 are able to close the valve 17, thus raising the delivery pressure of the first stage, and reapplying the motive force, either wholly or in part, for the return stroke of the pistons 21.

As already indicated, it is not essential to the invention that the output of the pump should be controlled in accordance with variations in the output pressure; the output pressure of the first stage may instead be relieved by a mechanically operated valve. In such cases the construction of the pump may be precisely as above described and as shown in the accompanying drawings except for the means provided to actuate the relief valve 17. The channel 31 by which the output pressure is applied to this valve is omitted and means are provided for mechanically opening the valve, these means being actuated either manually or by a member which is operated by the output of the pump.

The invention claimed is:

A two stage power driven fluid pump comprising a casing, a partition in said casing dividing same into a first chamber and a second chamber, a pump shaft extending through said chambers, means for admitting a working fluid to said first chamber, a gear pump unit in said first chamber including intermeshing gears actuated by said shaft to impart to said fluid a pressure dependent upon the speed of rotation of said gears, means for discharging the fluid output of said gears from said first chamber into said second chamber, a piston pump in said second chamber including a plurality of cylinders disposed radially of said shaft, pistons in said cylinders, means on said shaft for actuating said pistons in one direction only, means for supplying fluid under pressure in said second chamber to said cylinders at a rate dependent upon the output pressure of said first chamber to actuate said pistons in the opposite direction, means for discharging fluid under pressure from said second chamber, and means including a valve between said first and second chambers and subject to the fluid pressures in said chambers to control the output pressure of said first chamber and thereby control the volume of fluid supplied to said cylinders and thus the effective stroke of said pistons.

RONALD FREDERICK WORLIDGE.
